UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT-STOCK COMPANY OF FRANCE.

SUBMARINE MINE.

1,321,775.

Specification of Letters Patent. Patented Nov. 11, 1919.

Application filed September 4, 1917. Serial No. 189,587.

To all whom it may concern:

Be it known that I, EUGÈNE SCHNEIDER, a citizen of the Republic of France, residing at Le Creuzot, France, have invented 5 a new and useful Improvement in Submarine Mines, which is fully set forth in the following specification.

This invention relates to submarine mines for blockading purposes, constructed in 10 such a manner that the whole arrangement constituted by the float and the sinker, shall first sink to the bottom, whereupon the float will become separated from the sinker and will ascend toward the surface of the water 15 and remain at a predetermined distance below the surface.

Mines of this kind have already been proposed wherein the immersion of the float to the desired depth is effected by causing the 20 cable that connects the float to the sinker, to be acted upon by a device such as a hydrostatic piston fixed to or near the float.

These known mines necessitate a special 25 construction both of the float and of the sinker.

The present invention is now designed to achieve the above stated object by means of devices which are wholly located in the sinker, thereby dispensing with the necessity of a special construction of the said 30 sinker.

A mine constructed according to this invention comprises, like the known mines, a hydrostatic device for actuating the stop 35 pin of the windlass from which the buoy rope connecting the float to the sinker is unwound; this device coming into operation after the float has become separated from the sinker at the bottom of the sea, that is 40 to say, at the point or near the point where the sinker is resting on the bottom.

According to this invention all the parts for effecting the regulation of the depth of immersion are located in the sinker. For 45 this purpose the sinker contains in addition to the windlass and its stopping device, the hydrostatic device for actuating the said stopping device. This hydrostatic device is subjected on one face or side to the pressure 50 corresponding to the depth at which the sinker is situated, and it is subjected on its other face or side to a constant pressure, for instance, atmospheric pressure. It is further subjected to an opposing action of a 55 movable part which is adapted to be moved

by the unwinding of the buoy rope. The action of this part will come into operation as hereinafter described by reason of the pre-affected regulation of its starting position, at the exact moment when the length 60 of the cable that is still unwound is equal to the selected depth of immersion of the float. In other words the length of the buoy rope that has been unwound up to the time of the ascent of the float, is less than 65 the depth of the sea at the anchoring place, by an amount which is equal to the selected depth of immersion of the float.

This invention will now be more particularly described with reference to the accompanying drawings which illustrate by way of example an embodiment of the present invention. 70

In these drawings:—

Figure 1 is a plan of the general arrangement of the improved apparatus for regulating the depth of immersion, located wholly in the sinker. 75

Figs. 2 and 3 are vertical sections taken respectively on the lines II—II and III— 80 III of Fig. 1.

Fig. 4 is a diagram illustrating the manner in which the arrest of the main float at the desired depth of immersion may be effected by pre-regulation of the starting 85 point of the movable part that is actuated by the unwinding of the buoy rope, and that acts upon the hydrostatic device.

In the example shown, the hydrostatic device consists of a valve K supporting on its 90 upper face having a cross sectional area S, the pressure that exists at the place where the sinker has sunk to the bottom. The other face of the valve K communicates with a watertight chamber containing air at atmospheric pressure. 95

The valve is connected to one of the arms G¹ of a rocking beam G—G¹ which is balanced by a suitable weight and is pivoted at a point X (Fig. 4). 100

The movable part which is actuated by the unwinding of the buoy rope, and which by moving the valve K, will produce the engagement of the device for stopping the windlass at the desired moment, always exerts an effort p upon the arm G, while its point of support is shifted along the said arm. 105

It may be assumed that the movable part exerts its effort p at X (at the pivot point of 110

the rocking beam) at the instant when the buoy rope is completely wound on the windlass, while the movements imparted to the said part are such that the said part will 5 arrive at the end Y when the buoy rope (which has a length corresponding to the maximum depth of descent of the sinker) has been completely unwound. Under these conditions it will be understood that the 10 distance L of the point of application of p at X is constantly proportional to the length of the buoy rope unwound during the ascent of the float, and consequently to the distance between the said float and the bottom at the 15 place of anchorage.

If P be the pressure per superficial sq. cm. upon the valve K at the maximum depth of immersion H , and l be the length of the arm G^1 , then the moment of the force tending to 20 keep the valve K upon its seat will always be $= P \cdot S \cdot l$. On the other hand, the moment of the force exerted by the movable part upon the arm G will vary from 0 to $p \cdot L$, if as above stated, it is assumed that 25 the force is acting at X when the buoy rope is fully wound, and is acting at Y when it is fully unwound, the sinker being immersed at the maximum depth H .

It will be understood that by means of a 30 suitable controlling mechanism it is possible in the meantime to cause the leverage of the force p to vary proportionately to the length of the buoy rope that has been unwound.

Moreover, the opposing force p may be determined in such a manner that its moment shall become preponderant at the instant when the movable part is situated at Y, the 35 sinker being assumed to be immersed at the maximum depth H , equal to the total length 40 of the buoy rope wound on the windlass. The value of p will then be

$$p = \frac{P \cdot S \cdot l}{L}.$$

45 If the mine is submerged at a point where the bottom is situated at any intermediate depth, for instance h , then the moment of the force acting upon the valve K will be

$$p = \frac{P \cdot S \cdot l \cdot h}{H}.$$

Now since the path of p is proportional to the length of unwound buoy rope, then 50 when the float reaches the surface this length will be

$$L' = \frac{L \cdot h}{H},$$

55 and the moment of p will be

$$\frac{P \cdot S \cdot l}{L} \cdot \frac{L \cdot h}{H} = \frac{P \cdot S \cdot l \cdot h}{H}$$

60 The rocking movement of the rocking beam for effecting the locking or arrest of

the windlass will be produced at that moment, while it would have been produced at Y if the sinker should have been sunk to the depth H . Therefore the locking or arrest of the windlass will take place at the moment 70 when the float arrives at the surface of the water, irrespectively of the intermediate depth at which the mine is anchored.

If now the rocking beam (which is released only when the mine touches the bottom) be 75 locked for the time being and if the mine is submerged after having given to the part that exercises the force p , a certain lead L'' corresponding to a fraction of L equal to $\frac{L''}{L}$, 80

and consequently to a depth equal to $\frac{L'' \cdot H}{L}$, 85 it will be readily understood that whatever may be the depth of the immersion, the moments will balance one another, and the windlass will be locked when the float shall be situated at a distance equal to $\frac{H \cdot L''}{L}$ 90 from the surface. Therefore in order to attain the immersion of the float at a determined depth, it will be sufficient beforehand to shift the movable part exerting the force p , to an extent corresponding to the desired immersion.

95 As shown in Figs. 1 to 3, the several mechanisms necessary for regulating the depth of immersion are located in the sinker A.

The windlass drum B for winding and unwinding the buoy rope b^3 , is journaled in two 100 brackets fixed to the brace a^1 of the sinker. The first bracket b^1 is an ordinary bracket, and the second bracket b^2 is combined in a well known manner with a brake that will prevent the windlass drum from unwinding 105 the buoy rope so long as the float C does not exert any pull upon it. The said brake also serves to limit the speed of unwinding when the apparatus is operating.

The main stop member D is under the action of a spring d^1 which has a constant tendency to move the stop into engagement with a ratchet wheel B^1 fixed to the windlass drum; the stop member being held out of engagement by a catch d^2 which is pivoted at 110 d^3 , and engages in a notch in the stop member, and is itself acted upon by a spring d^4 . When the catch d^2 , actuated by the hydrostatic device, releases the main stop member D, then the latter will lock the windlass 115 drum.

The buoy rope b^3 is wound upon the windlass drum and is fixed at one end to the said drum, while its other end, after passing through a guide eye a^2 , engages in the 120 groove of a pulley E and is then fixed to the float by means of an eye bolt e^1 , after having passed through a second eye a^3 fixed in the top of the sinker.

125 The pulley E is fixed on a shaft e^1 jour-

naled in brackets e^2 fixed to the sinker bottom a^1 . On the end of the said shaft there is fixed a pinion e^3 engaging a pinion e^4 fixed on a screw spindle e^5 mounted in the 5 bracket e^6 and adapted by its rotation to shift a traveler F. This traveler is guided by means of two side pieces in two grooves of a guiding and supporting member f^1 fixed to a wall of the sinker.

10 A bell crank lever f^2 which is pivoted on an axle f^3 fixed on the traveler, carries at the end of its lower arm a roller f^4 . The end of the upper arm of the said lever is attached to a spring f^5 whose tension for producing the constant force p , is regulated by means of a screw f^6 passing through an eye f^7 in an extension of the traveler and upon which works a nut f^8 .

15 The roller f^4 bears on the upper surface of the arm G of a rocking beam G—G¹. This surface is exactly parallel to the axis of the screw spindle e^5 . The roller transmits the pressure p of the spring to the arm G. The rocking beam is pivoted on an axle g^1 (that is, the axis X of the diagram) journaled in a bracket g^2 fixed to the sinker bottom a^1 .

20 K is a valve working in a cylinder k^1 ; it rests on a seat k^2 which limits its downward movement. The valve spindle is connected to the arm G¹ of the rocking beam by means of a pin g^3 .

25 g^5 is a balanced weight screwed on a screw-threaded extension g^4 of the arm G¹.

30 The axle b^4 of the windlass drum B carries on a screw-threaded portion a traveler b^5 which locks the rocking beam so long as the windlass drum has not made a determined number of unwinding turns; it carries at its end a crank designed to allow of the buoy rope being wound on the windlass drum.

35 The screw spindle e^5 may also be provided on its end e^7 with a crank by means of which the traveler F can be moved by hand for the purpose of thereby regulating, at the time of anchoring, the depth of immersion which it is desired to give to the float.

40 The float is held on the sinker in any desired manner until the instant when the whole, namely the float and the sinker, has sunk to the bottom or near the bottom of the sea.

45 The operation of the improved apparatus is as follows:

50 The depth of immersion which it is desired to give to the mine is regulated by sliding the traveler F through a determined distance. The mine is then ready to be sunk.

55 After the sinking the whole arrangement constituted by the floating mine and the sinker rests on the bottom. At the end of a certain time the float mine is released and rises toward the surface, unwinding the

buoy rope from the windlass drum; this operation being retarded by the brake b^2 . When a few turns of the buoy rope have been unwound from the windlass drum, the traveler b^5 releases the rocking beam G—G¹ 70 which is kept at first in its original position by the pressure acting upon the valve K.

75 As the buoy rope unwinds, its friction in the groove of the pulley E drives the latter, and through the gearing $e^1—e^3—e^4—e^5$ moves the traveler F which is shifted through a distance proportionate to the unwound length of the buoy rope. When the traveler has moved through a distance such that the moment of the effort which it transmits to 80 the arm G will be greater than the moment of the valve K produced by the pressure existing at the depth of immersion h of the sinker, the effort of the traveler F will become preponderant and by its action, the 85 arm G will be moved down. In this movement the said arm meets and pushes back the catch d^2 , whereby the main stop member D is released which, being pushed forward by its spring d^1 , engages in the teeth of the 90 ratchet wheel B¹.

95 The stoppage of the windlass drum takes place exactly at the instant when the floating mine has reached the depth of immersion pre-determined by the adjustment of the traveler F, because the floating mine had still to pass, before arriving at the surface, through a length proportionate to the amount through which the said traveler had previously been shifted.

100 What I claim is:—

1. In a structure of the character described, the combination of a sinker, a mine carried thereby and secured thereto by a cable wound on a drum within the sinker and free to unwind under the rising action of the mine, means for locking the drum to stop the unwinding action, and hydrostatically controlled mechanism holding said locking means out of action until the mine 110 rises to a predetermined point.

2. In a device of the character described, a sinker, a mine carried thereby, a rotatable drum in said sinker, a cable wound on said drum and connected to said mine, the separation of said mine and sinker causing said cable to rotate said drum and be unwound therefrom, a stop device for said drum, and hydrostatically controlled mechanism for holding said stop device out of action.

115 3. In a device of the character described, a sinker, a mine carried thereon, a rotatable drum in said sinker, a cable wound around said drum and connected to said mine, the separation of said drum and mine as the latter rises causing said cable to rotate said drum and be unwound therefrom, a stop device for said drum, and means for releasing said stop device and consisting of a lever one arm of which is subjected to hydrostatic 125

pressure and the other arm of which is subjected to a pressure shifted from the fulcrum of said lever at a rate proportional to the length of cable unwound from said drum.

5 4. In a device of the character described, a sinker, a mine carried thereby, a rotatable drum, a cable wound on said drum and connected to said mine, the rising action of said mine causing the cable to rotate the drum 10 and be unwound therefrom, a stop device for said drum, and mechanism for tripping said stop device, said mechanism comprising a two-armed lever and means for applying force to each arm of said lever, one of said 15 forces being hydrostatic pressure, and the means for applying force to the other arm being both manually and automatically shiftable.

5. In a device of the character described, 20 a sinker, a mine carried thereby, a rotatable drum in said sinker, a cable wound on said drum and connected to said mine, the separation of said mine and sinker causing said cable to rotate said drum and be unwound 25 therefrom, a stop device for said drum, a two-armed lever, means applying hydrostatic pressure to one of said arms, a pressure-applying means shiftable along the other arm proportionally to the unwinding 30 of said cable, said lever being in operative relation with said stop device to trip and free the same.

6. In a device of the character described, 35 a sinker, a mine carried thereby, a rotatable drum in said sinker, a cable wound on said drum and connected to said mine, the separation of said mine and sinker causing said cable to rotate said drum and be unwound therefrom, a stop device for said drum, a 40 lever, means applying hydrostatic pressure to shift said lever in one direction, and pressure applying means shiftable along said lever proportionally to the unwinding of said cable, said lever being in operative relation 45 with said stop device to trip and free the same.

7. In a device of the character described, 50 the combination of a sinker, a mine carried thereby, a drum in said sinker, a cable wound on said drum and connected to said mine, the separation of said mine and sinker causing said cable to rotate said drum and be unwound therefrom, a stop device for said drum normally held out of action, a lever, a 55 movable surface exposed to hydrostatic pressure and tending to shift said lever in one direction, a traveler movable along said lever and tending to shift it in the reverse direction, manually operable means for initially adjusting the position of said traveler 60 on said lever, automatic means operated by said drum and shifting said traveler proportionally to the unwinding of the cable, and means operable by said lever to free said stop 65 device.

8. In apparatus for regulating the depth of immersion of floating mines anchored to the bottom by a sinker connected by a buoy rope to the floating mine, the combination with a windlass drum having a constant 70 tendency to unwind the buoy rope, of a hydrostatic device consisting of a movable diaphragm located in the sinker, and subjected during the unwinding operation on one side to the pressure due to the depth of the sinker 75 in its anchoring position, and on the other side to a constant pressure existing in a closed chamber, a movable part adapted to be moved by the unwinding of the buoy rope proportionally to the amount of said unwinding, and to transmit to said diaphragm an opposing effort having a variable leverage, which said effort is caused by the pre-adjustment of the initial position of said movable part, to become preponderant at the instant when the unwound length of the buoy rope is equal to the predetermined depth of immersion of the floating mine.

9. In apparatus for regulating the depth of immersion of floating mines anchored 90 to the bottom by a sinker connected by a buoy rope to the floating mine, the combination with a windlass drum having a constant tendency to unwind the buoy rope, of a hydrostatic device consisting of a movable 95 diaphragm located in the sinker, and subjected during the unwinding operation on one side to the pressure due to the depth of the sinker in its anchoring position, and on the other side to a constant pressure 100 existing in a closed chamber, a balanced rocking beam one arm of which is connected to said hydrostatic device, a traveler adapted to exert a constant opposing effort upon the other arm of said rocking beam, movable 105 along a rotating screw, said screw being rotated through gearing by the pull of the unwinding buoy rope proportionally to the unwound length of the latter, a guide in said sinker wherein said traveler can be given, 110 relatively to the rocking axis of said rocking beam, an initial position corresponding to the pre-determined depth of immersion of the floating mine.

10. In apparatus for regulating the depth 115 of immersion of floating mines anchored to the bottom by a sinker connected by a buoy rope to the floating mine, the combination with a windlass drum having a constant 120 tendency to unwind the buoy rope, of a hydrostatic device consisting of a movable diaphragm located in the sinker, and subjected during the unwinding operation on one side to the pressure due to the depth of the sinker in its anchoring position, and on the other side to a constant pressure existing in a closed chamber, a balanced rocking beam one arm of which is connected to said hydrostatic device, a traveler movable along a 125 rotating screw, said screw being rotated 130

through gearing by the pull of the unwinding buoy rope proportionally to the unwound length of the latter, a bell-crank lever pivoted to said traveler, a roller mounted on one arm of said bell-crank lever, adapted to bear upon the other arm of said rocking beam, and a spring attached at one end to the other arm of said bell-crank lever, and attached at its other end adjustably to a fixed point of said traveler, where-

by a constant opposing effort is exerted upon said other arm of said rocking beam.

In testimony whereof I have signed this specification in the presence of two subscribing witnesses.
